PROCESS OF FINISHING PRINTING PLATES

William H. Banzett, Clifton, N. J.

Application August 13, 1937, Serial No. 158,948

1 Claim. (Cl. 161—401.3)

The purpose of this invention is to improve the method of finishing the printing surface or face of printing plates to eliminate all irregularities and unevenness in the printing or contacting surface of characters or type thereof.

The invention is the art or process of planing, grinding or lapping the printing surface or face of electrotype, stereotype, or other typographic or raised character printing plates, which may be flat or curved in order to provide absolutely true or even contacting surfaces of the type, characters, or the like, thereof, and, at the same time, providing an absolutely true, flat or cylindrical finished surface.

10 The irregular height of type faces on duplicated or molded printing plates requires considerable "make ready" work, and padding of both the mounting for the plate and also of the impression surface or cylinder, and, although metal has been planed from the back of the plate, it still leaves irregular type faces or printing faces.

15 The individual type characters or linotype slugs, rules, borders, etc., are locked in a chase. The chase itself is a surrounding body at right angles to the clamping means. This is then set upon a "stone", a smooth level surface, and all characters or line slugs are beaten or hammered from the back so as to try to get the printing face in a true plane, but this is almost impossible as, as one section is beaten down, the other section slips a little, etc.

20 For an electrotype this locked up original, or master form, is pressed into wax to get an impression in reverse of the type face and the wax impression is black leaded to give it a metallic conducting surface. It is then suspended in an electrocopper plating solution, and by electro-deposition, a copper shell is deposited on the wax, usually from .006" to .010" thick. This shell is 25 stripped from the wax, cleaned in various ways, and the back face is tinned by melting tinfoil over the copper so that the heavy type metal 30 backing will adhere to the shell when it is poured into it in a molten state.

25 The stripping of the copper shell from the wax, the "tinning" and applying the hot backing metal, all distort the printing face from its original "nearly" true plane. It is then placed upon a true surface and again beaten from the back to try 35 to bring the printing face to a true plane.

30 There are various ways of doing this, either manually or by mechanical means, but they all have the final objective of trying to get all type faces to a true plane.

35 After the face is approximately true, the excess

of backing metal is shaved off, and the plate is then trued up to the face again, and shaved from the back.

40 After all of these manipulations are completed at great expenditure of time and labor, the accuracy is really dependent on the skill of the operator.

45 It can readily be seen that a short or small displacement of the type face cannot be completely corrected from the back of the plate.

50 In the case of stereotypes the same lockup is pressed against a wet paper "mat", and heat is applied to the mat from the opposite side until the paper is dry and hard. This mat then forms a face mould into which melted stereotype metal 55 is poured to make the complete plate, either flat or curved, the theoretical curves actually proving a series of chords approximating a circle, as the face of all characters is originally flat.

55 Inaccuracies of varying thickness of "mat", 20 distortion of original lockup and pressure while being heated, and distortion while the hot metal is being cast, all contribute toward errors and irregularities.

60 Various ways of bending the electros to cylindrical form after shaving approximately true are used, and "hot forming fixtures" are applied to try to get true curved plates. Another type of printing plate is made by moulding plastics such as "bakelite" into a mould, and as this mould is 65 made from type, locked up in a chase, the irregularities are also present.

65 All of these irregularities must be corrected in a manner known to the trade as "make ready" on the press, which is a slow costly operation as an 70 expensive press is idle during this time. It is therefore desirable to eliminate a large portion of this "make ready" time that ties up the expensive press, and, at the same time, improve or 75 perfect the actual contacting printing face of 80 the type or plates.

75 The object of this invention is, therefore, to eliminate all irregularities in the printing face of type, and, at the same time, provide plates, the 85 printing surface of which is parallel to the back so that the distance through the plate is equal at all points, and, particularly in cylindrical printing, the plate may be mounted upon a true cylinder without underlays, so that the "make ready" 90 time is reduced to a minimum or eliminated.

80 Another object is to provide a method of compensating for unevenness of single characters, such as a bold letter "I", by grinding off the ends, making the surface of the letter in an arc instead of a straight line, thereby making it pos- 95

sible to obtain an even impression throughout the length thereof.

A further object is to provide an improved method for finishing the printing surfaces of printing plates, in which the plates may be finished, ready for use, on a separate machine, and then readily mounted upon a printing cylinder, in which the printing cylinder may be perfectly round without the use of underlays or the like.

A still further object is to provide an improved method for finishing the printing faces of printing plates, in which the contacting surface forms an absolute cylinder, eliminating the necessity of overlays on the impression cylinder to compensate for irregularities as is normally the case.

And a still further object is to provide an improved method of obtaining an absolutely even contacting or printing face of printing plates or type, which is relatively simple and inexpensive.

Other features and advantages of the invention will appear from the following description taken in connection with the drawing, wherein:

Figure 1 is a diagrammatic view showing a printing plate with uneven contacting or printing surfaces of characters or type thereof, greatly exaggerated in order to illustrate an actual condition.

Figure 2 is a similar view with the unevenness also exaggerated showing a curved plate.

Figure 3 is a view showing a printing plate mounted upon a grinding machine, in which the grinding machine is incomplete, and only used for the purpose of illustration.

Figure 4 is a view showing a method of attaching a printing plate to the surface of a cylinder for grinding the face thereof.

The electrotypes, stereotype, or plastic printing plate is made in the usual manner of the art as accurate as good trade practice demands, and this plate is mounted with its finished back on a true surface, either a flat or curved plane. In order to true up the printing surface or type face, metal or material is removed from the face in what may be termed a super refining process, preferably on a separate machine, and, although the parts are shown exaggerated in the drawing, it will be understood that only a few one-thousandths of material are removed, however, with the ordinary printing plate this is sufficient to provide an absolutely true surface. On very slender type this requires a very fine grinding process, or a lapping process, and, when finished, the thickness of the plate, or the distance from the face to the back is absolutely equal at all points.

In the drawing a flat printing plate is indicated by the numeral 1, and this is placed upon a "stone" 2 having an absolutely true face or exposed surface 3, and it will be noted that the type or characters of the plate 1 engage the face 3 at a plurality of points, and if these faces were machined off, all of them would rest against and engage the surface 3. These faces are considerably exaggerated in the drawing, however, it will be noted that by hammering on the back some of these faces may be forced down until they engage the surface 3, although to force such type, as indicated by the numeral 4, between the type 5 and 6 downward upon the surface 3 would be very difficult, and it would also be very difficult and practically impossible to line up a bevel surface such as that of the type indicated by the numerals 7 and 8 without damaging the printing face. With any process used up to the present time, which involves forcing the type

from the back of the plate, it is substantially impossible to obtain an absolutely true printing face, so that it is necessary to pad the impression plate or cylinder, and also use considerable padding behind the printing plate.

Another plate is shown in Figure 2, in which the plate 1 has been formed around a curved or cylindrical surface, and it will be appreciated that in bending the plate the hard type surface does not bend, and the bending takes place in the body of the plate, which is indicated by the numeral 9. This figure illustrates the uneven type surfaces 10 on the upper side, whereas, after they pass the grinding wheel 11, these surfaces are absolutely even, providing a true cylindrical surface 12.

In Figure 3 a simple form of grinding machine is shown, in which the printing plate 9 is mounted upon a cylinder 13, and the cylinder is mounted on a shaft 14 in bearings 15 on a base 16, and a grinding wheel 17 is mounted on a traveling carriage 18 and rotated by a motor 19 through a belt 20. It is understood that this is only a typical arrangement, as the grinding wheel may be mounted and operated in any manner or by any means.

In Figure 4 the plate 9 is shown attached to the face of the cylinder 13 by clamps 21, however, it will be understood that this plate may be mounted upon the cylinder, or upon a flat plate 30 or any means in any manner or by any means. It will also be understood that any means may be used for surfacing the exposed surface, or turning, grinding, or lapping the surface in order to remove all unevenness or irregularities, and this may be accomplished by machine or any means.

This operation or process provides a printing plate with a true flat or curved surface, and that is of equal thickness from the printing face to the back at every point, and, as the final finishing may require the removal of different amounts of metal or material from the face of the plates, each plate will be of an even thickness in itself, however, one plate may vary from another of the same set, and the plates should, therefore, be prepared by refinishing the back or inside to a predetermined thickness, or various uniform thicknesses of sheets of material, such as paper, may be added to the back to compensate for varying finished thickness in order to make the total thickness of all plates equal.

Lapping or finishing the face of the type in this manner also provides sharp edges, so that even worn electrotypes, or any typographic plates, could be relapped or refinished to bring up sharp printing instead of replacing plates with new ones on long runs.

It will be understood that changes may be made in the process without departing from the spirit of the invention. One of which changes may be in the use of any other type of machine or mechanism for holding the plate while being lapped or finished, another may be in the use of any other process for removing material from the face of the type or plate, and still another may be in the use of this process for obtaining a true printing surface on devices for any other purpose.

The process or operation thereof will be readily understood from the foregoing description, and it will be understood that plates finished in this manner will provide an absolutely true even printing face or surface, and it will be of even thickness throughout, and may be used on true

cylinders instead of cylinders composed of hills and hollows, thereby eliminating the jerks and jumps of the paper caused by the paper passing over an uneven or irregular printing surface.

5 Having thus fully described the invention, what I claim as new, and desire to secure by Letters Patent, is:

The process of finishing a duplicate relief printing plate having a plurality of lines of characters

or the like on the printing face, and of the type made from a master mold; which comprises mounting said plate upon a true base and removing material from the printing face thereof to correspond to said base, the distance from the printing face to the back of the finished plate being equal at all points.
